UNITED STATES PATENT OFFICE

2,262,549

PRINTING PRESS

James Edward Gilbert, Chicago, Ill., assignor to
Columbian Bank Note Company, a corporation
of Illinois

Application April 28, 1939, Serial No. 270,635

18 Claims. (Cl. 101—162)

This invention relates to improvements in printing presses and more especially a power printing press especially adapted for taking impressions from etched or engraved plates, and for intaglio work in general.

Among the features of my invention is the provision of means for wiping the plate with wiping material over a wiper roller rotated counter to the direction of movement of the plate during the wiping operation, thus avoiding the accumulation of ink in front of the wiping face and the resultant objectionable unevenness in ink removal heretofore encountered in presses of this sort.

Another feature of my invention is the provision of means for employing the same wiper cloth for both wiping and polishing, thus effecting a saving in the cost of operation.

Another feature of my invention is the provision of means whereby the same portion of the wiper cloth first used for polishing, is then used for wiping, thus effecting a saving in the cost of material and operation.

Another feature of my invention is increased simplicity in construction and operation with respect to the plate travel and impression roller oscillations, for performing the various printing operations, whereby the length of travel of the plate and therefore the overall length of the press has been considerably shortened. This has been accomplished by performing the wiping and polishing operations in immediate succession at one end of the plate travel as the plate leaves and returns to its position under the impression roller. During the latter part of each return movement of the plate it is inked; and during the latter part of each forward movement it is wiped. During the forward movement the impression roller receives the paper. During the return movement the plate is first polished and then gives its impression to the paper. Thereafter, but still during this return movement, the impression roller delivers the paper. All these operations are accomplished by continuous reciprocations of the plate synchronized with continuous oscillations of the impression roller thus giving smooth, rapid and efficient operation.

Other features and advantages of my invention will appear more fully as I proceed with my specification.

In that form of device embodying the features of my invention, shown in the accompanying drawings—Fig. 1 is a view in side elevation; Fig. 2 is a similar view showing the opposite side; Fig. 3 is a top plan view of the receiving end of

the press with the feed table removed; Fig. 4 is a top plan view of the delivery end of the press; Fig. 5 is a view taken as indicated by the line 5 of Fig. 3; Fig. 6 is a view taken as indicated by the line 6 of Fig. 4; Fig. 7 is a view taken as indicated by the line 7 of Fig. 3; Fig. 8 is a view taken as indicated by the line 8 of Fig. 3; Fig. 9 is a similar view showing the parts in another position; Fig. 10 is a view taken as indicated by the line 10 of Fig. 3; Fig. 11 is a view taken as indicated by the line 11 of Fig. 10; Fig. 12 is a view taken as indicated by the line 12 of Fig. 1; Fig. 13 is a view in side elevation of the wiper roller jogging mechanism; Fig. 14 is a view taken as indicated by the line 14 of Fig. 13; Fig. 15 is a view taken as indicated by the line 15 of Fig. 13; Fig. 16 is a view taken as indicated by the line 16 of Fig. 15; Fig. 17 is a view taken as indicated by the line 17 of Fig. 18; Fig. 18 is a view taken as indicated by the line 18 of Fig. 13; Fig. 19 is a view taken as indicated by the line 19 of Fig. 18; Fig. 20 is a view taken as indicated by the line 20 of Fig. 1; and Figs. 21 and 22 are diagrammatic views showing the sequence of operations.

A general description of the construction and operation of the press will be helpful before proceeding to a more detailed discussion. For this purpose attention is directed to Figs. 21 and 22. As here shown, 10 indicates the press bed or plate carrier carrying the plate 11. 12 is the inking roller; 13 indicates the impression roller; 14 the wiping and polishing roller, having over it a strip of material 15 for wiping and polishing such as, for example, paper, cloth or the like. 16 indicates the feed table at the receiving end of the press upon which the paper is placed preparatory to its being removed by the impression roller for the printing operation.

The plate carrier 10 reciprocates back and forth horizontally. In Fig. 21 it is shown at the extreme lefthand end position of its travel. In Fig. 22 the extreme right-hand end of its travel is indicated by the broken lines at the extreme right. The impression roller 13 oscillates through a distance of approximately 630°. As the plate moves from left to right, which may be referred to as its forward movement, the impression cylinder 13 is raised from contact with the plate and rotates counterclockwise, which may be referred to as its return movement. During the forward movement of the plate, the inking roller 12, which has already inked the plate during the last part of the preceding return stroke, is out of contact with the plate and in contact with

the ink supply mechanism. During the latter part of the forward movement the plate is wiped by the roller 14. During the return movement (from right to left) of the plate, the impression roller 13 rotates in a clockwise direction to take the impression from the plate, and after the plate leaves the roller, the latter continues far enough to deliver the printed sheet to the delivery conveyor 17 at the delivery end of the press. During this return movement of the plate, it is first polished by the roller 14, the impression is taken, and the ink roller 12 is dropped so that the plate is inked as it returns to the starting point.

Plate carrier and its operating mechanism

The plate carrier 10 is mounted for reciprocation on the supporting rollers 20, carried on the bed 21. At the center of the press, under the impression roller, is a supporting roller 23 extending entirely across the press, which in turn is supported on the rollers 24, 24 carried on the frame member 25. This roller 23 is very heavy and rigid, and being located directly under the impression cylinder, gives firm and solid support to the plate carrier directly under the point of contact where the impression is taken. At each side the plate 10 is provided with a rack bar 26, engaged by teeth 27 at the ends of the roller 23. At the ends of the travel of the plate carrier, the teeth 26, after they leave the teeth 27, are engaged by teeth 28 on the gears 29, and teeth 30 on the gears 31. That is, the gears 29 are at the receiving end of the press and serve to move the plate carrier at the commencement of its forward movement. After leaving the teeth 28, the plate carrier is engaged by the teeth 27 on the roller 23 and after leaving these, the forward movement of the plate carrier is completed by means of the teeth 30 on the gears 31.

The following means are provided for oscillating the roller 23 and the gears 29 and 31 in order to reciprocate the plate carrier. 32 indicates a driven wheel on the transverse shaft 33 carrying a pinion 34, driving the gear 35 on a shaft 36 which, in turn, by means of the pinion 37 drives a large gear 38 on the crank shaft 39. The crank shaft 39, by means of the crank 40 and connecting rod 41, oscillates the toothed segment 42 pivoted at 43. This segment, by means of the pinion 44, oscillates the transverse roller 23 above described. The gears 29 and 30 are oscillated from this roller through intermediate pinions as follows. The roller 23 carries the gear wheel 45, driving the gear 46 which, in turn, drives the shaft 47 (on which the pinions 29, 29 are mounted) by means of the gear 48. Likewise, at the other end of the press, the gear 45 drives the gear 49 which, in turn, drives the gear 50 on the shaft 51 which carries the gears 31, 31.

Impression cylinder and its operating mechanism

The impression cylinder 13 is mounted on a shaft 54, the ends of which are journaled in the journal blocks 55, slidably mounted for vertical movement in the guides 56 at the sides of the press.

The impression cylinder 13 is oscillated in the following manner. At each end, the cylinder is provided with teeth 57 engaged by rack bars 58 carried at the sides of the plate carrier 10. The rack bars 58 are formed integrally with the rack bars 26, the teeth on the upper surface constitute the upper rack bars 58, and the teeth on the lower surface constitute the lower rack bars 26. Accordingly, it will be seen that reciproca-

tions of the plate carrier 10 serve to oscillate the impression cylinder 13. The engagement of the teeth on the rack bar 58 with the teeth on the gears 57 is sufficiently deep so that they will remain meshed, and the oscillations of the cylinder 13 will continue even when the cylinder is slightly raised, as will be described hereinafter.

As has been stated before, the impression cylinder is in its raised position, or out of contact with the plate, during the forward movement of the plate. During the return movement, it is in its lower position to take the impression. The vertical movements of the impression cylinder are accomplished in the following manner.

15 The transverse shaft 36, through the bevel gears 60 and 61, drives a longitudinal shaft 62 which, in turn, through the bevel gears 63 and 64, drives a transverse shaft 65 carrying the cam wheel 66 with the cam groove 67 embracing the cam roller 68 on the bell crank 69 pivoted at 69a.

20 The bell crank 69, through the connecting rod 70, oscillates the bell crank 71, pivoted at 72, carrying the vertical rod 73, the upper end of which is pivoted to the crank 74 on the transverse shaft 75, carrying a similar crank 76 at the opposite side of the press. The swinging ends of the levers 74 and 76 are attached to vertical rods 80 and 81, respectively, having their upper ends attached to cranks 82 and 83, respectively, attached to eccentrics 84, one at each side of the press above the vertically slidable journal blocks 55. The journal blocks 55 are yieldingly urged upwardly by the springs 85. Rocking of the arms 74 and 83 serves to rock the eccentrics 84 to depress the journal blocks 55 against the upward pressure of the springs 85. The vertical movement of the impression cylinder is very slight, as all that is necessary is to raise it enough to cause the blanket to clear the plate during the forward movement of the plate carrier. The parts are so timed, accordingly, that when the plate moves forward, the arms 74 and 83 are rocked so that the impression cylinder will be held in its raised position by the springs 85. When the impression is to be taken, the arms 74 and 83 are reversely rocked to operate the eccentrics to lower the journal blocks 55 to move the impression cylinder into its lowermost position to cause the paper to contact with the plate to take the impression as the plate moves from right to left as viewed in Fig. 22. In Fig. 21 the impression cylinder is shown in its upper position and in Fig. 22 it is shown in broken lines in its lower position.

55 Permanent vertical adjustment of the impression cylinder 13 is effected by means of the screws 90 having their lower ends bearing against the bearing blocks 91 below which the eccentrics 84 are mounted. The screws 90 are carried on vertical shafts 92 adapted to be rotated by the worm gear 93 meshing with the worm 94, adapted to be operated by the hand wheel 95, so that both ends of the cylinder are simultaneously raised or lowered an equal distance by one operation.

60 The following means are provided for disconnecting the means for vertically reciprocating the impression cylinder. This may be accomplished by disengaging the connecting rod 70 from the bell crank 69. As seen in Fig. 1, the connecting rod 70 is not permanently fastened to the bell crank 69, but is provided at its end with a hook 70a engaging a pin on the bell crank 69. Means are provided for moving the left-hand end of the connecting rod 70 upwardly to disengage the hook from the pin. As here shown,

such means include the pivoted lever 100 with a roller 101 lying under the connecting rod 70. A pedal 102 is provided for rocking the lever 100 upwardly to cause the roller 101 to lift the rod 70 and disengage the hook 70a from the pin. Connection between the pedal 102 and arm 100 is effected by means of the rock lever 103 and short connecting rod 104 as shown in Fig. 1. As soon as the mechanism is disconnected, the springs 85 will automatically raise the impression cylinder to its uppermost position.

Inking mechanism

The inking roller 12 is inked by means of the two fountain rollers 105 and 106 carrying an ink supply 107 between them. The fountain rollers 105 and 106 are driven in the direction indicated by the arrows in Fig. 5 by means of the motor 108 operating through the train of gears indicated in general by 109. This rotation of the fountain rollers 105 and 106 is continuous.

When the inking roller 12 is in its lower position to ink the plate, during the return movement of the latter, said ink roller 12 is out of contact with the fountain roller 106. When it is raised, during the time that the plate makes its forward movement, it is in contact with the roller 106 to receive a fresh ink supply. The ink roller 12 is not positively rotated by any mechanism, but is rotated by the contact with the plate when in its lower position and by contact with the roller 106 while receiving its ink supply in the upper position. By arranging the apparatus so that the plate is inked during the latter part of the return stroke both the plate and the fountain roller tend to rotate the inking roller 12 in the same direction and at substantially the same rate. This avoids any undue strain on the parts, as would be occasioned by the plate having to reverse the rotation of the inking roller if inking were effected during forward movement.

The ink roller is vertically reciprocated in the following manner. The shaft 65 carries a cam 110 with a cam groove 111 embracing a cam roller 112 on the crank 113 pivoted at 114. The shaft 114 extends transversely of the press and carries an arm 115 (similar to the arm 113) on the opposite side. The arms 113 and 115 operate through similar mechanism on each side of the press to raise and lower the ink roller, and consequently, I shall describe only the mechanism on one side. The arm 113 operates through the link 116 to rock the transverse shaft 117 by means of the crank 118. At each side of the machine the transverse shaft 117 carries an eccentric which, in turn, carries the lower end of a vertical shaft 119, the upper end of which is attached to one end of the shaft 120 carrying the inking roller 12. Rocking of the shaft 117, therefore, operates through the eccentrics (not shown in detail) to reciprocate the ink roller 12 vertically, as originally described. The vertically movable rods 119 are mounted in suitable grooves in the frame of the machine to permit their vertical movement, and the ends of the shaft 120 are suitably journaled in the upper end of these rods 119.

In order to secure an even distribution of ink on the plate one of the fountain rollers is crowned. These rolls, each solid steel, are about twenty-eight inches long and six inches in diameter; but one of them is about one-hundredth of an inch greater in diameter at the center than at the ends. This overcomes the difficulty

which has heretofore made long fountain rollers impractical, the tendency to pass considerably more ink at the center than at the ends.

Gripping mechanism

The gripping mechanism comprises, in general, means in cooperation with the impression roller for gripping a sheet on the feed table so that the sheet will be held against the impression roller while the impression is taken. After an impression is taken, the impression roller continues its rotation in the same direction and finally the gripper is released and the paper discharged from the roller onto the delivery conveyor at the delivery end of the press.

As shown in the drawings, the gripping mechanism includes a series of upper gripping fingers 121 mounted on a shaft 122 and a series of lower delivery fingers 123 mounted on the shaft 124. The shafts 122 and 124 are both reciprocable to raise and lower the fingers. As shown in Fig. 8, the fingers 121 are lowered to grip the front edge 125a of a sheet of paper 125 lying on the feed table 16. 126, 126 indicate two positioning members against which the forward edge of the paper 125 is placed, preparatory to its being gripped by the gripping mechanism. Substantially, at the time the grippers grip the paper and commence to move it forward, the positioning members 126, 126 are swung upwardly and away from the paper to permit its removal. In Fig. 9 the gripper fingers 121 are raised, releasing the forward edge of the paper, the delivery fingers 123 raising the edge 125a from the roller so that continued rotation of the impression cylinder 13 will discharge the paper onto the bridging members 127 mounted on the shaft 128 from which the paper is discharged onto the delivery conveyor strips 129 at the delivery end of the press. The shaft 128 is rockable so that during the first part of the rotation of the impression cylinder, when the paper is to be carried to the plate for an impression, the pointed ends of the bridging members 127 are slightly elevated as shown in Fig. 8. When the paper is to be discharged, they are somewhat lowered and the gripper fingers are somewhat raised so that as the gripper fingers release the paper, its forward edge, raised by the fingers 123, will engage the bridging members 127, as shown in Fig. 9, to cause the paper to be delivered to the conveyor 129.

The following mechanism is provided for oscillating the shafts 122 and 124 carrying the fingers 121 and 123, respectively. The shaft 122 carries an arm 130 with a cam roller 131 engaging a movable cam 132. The position of the cam 132, in turn, is controlled by the pivoted lever 133 carrying a cam roller 134 engaging the cam 135 on a cam wheel 136. The shaft 124 carries an arm 137 having a cam roller 138 engaging a cam 139 carried by the lower end of the lever 140 pivoted at 141, the upper end of which carries a cam roller 142 adapted to engage another cam 143 on the cam wheel 136a. The cam 132 is yieldingly held outwardly by the spring 144. The cam roller 131 is yieldingly held against its cam by the spring 145. The spring 146 serves to hold the cam roller 142 against the cam wheel 136a.

The parts are so timed and coordinated, and the cams are so shaped, that the gripper fingers will lower to grip the forward edge of a sheet of paper as shown in Fig. 8 at the commencement of rotation of the impression cylinder in

the forward direction. In other words, as shown in Fig. 8, the impression cylinder has just completed its rotation in a clockwise direction and the gripper fingers have been raised and lowered to grip the forward edge of the paper, and the cylinder is ready to commence its rotation in a forward direction, that is, in a counterclockwise direction, as viewed in Fig. 8, to withdraw the paper from the feed table to take it down to the plate for an impression. In the position shown in Fig. 9, the impression has been completed and the cylinder is still continuing its rotation in a counterclockwise direction and the gripper fingers and delivery fingers have raised to cause commencement of delivery of the paper.

In Fig. 7 is shown the mechanism for retracting the positioning members 126 at the time the paper is withdrawn from the feed table by the impression cylinder. The fingers 126 are carried on an oscillating shaft 150 which is rocked by means of a cam roller 151 which is engaged by the cam 152 mounted on the shaft 153 which also carries the cam wheels 136 and 136a. When the roller 151 rides up on the cam, the positioning members 126 are swung to the left (as viewed in Fig. 7) by rocking the shaft 150. The shaft 150 carries an arm 155 adapted to engage a stop 156 to limit backward movement of the members 126. 157 indicates a spring to yieldingly urge the roller 151 in contact with the cam 152. Adjusting means including the screw 159 are provided for adjusting the position of the members 126.

The shaft 153 is driven from the shaft 160 through the gears 161 and 162. The shaft 160 is driven from the shaft 163 through the bevel gears 164 and 165. The shaft 163 is driven from the shaft 166 through the bevel gears 167 and 168. The shaft 166 is driven from the shaft 36 through suitable gears.

Wiping and polishing mechanism

The wiping and polishing is accomplished by means of a strip of wiping material 15 such as cloth, paper, or the like, over the wiping and polishing roller 14. The strip of material is preferably of a rough or ridged surface type, as burlap or paper creped into transverse ridges. The new material is supplied from the feed roller 170 and the used material rewound onto the roller 171. 172 is an idler roller over which the material lies before being bent over the roller 14. 173, 174, 175 and 176 indicate idler rollers over which the material is festooned. 177, 177 indicate rock arms carrying the rollers 178 and 179 constituting a suitable tensioning device. These parts may be seen diagrammatically in Figs. 21 and 22.

As has been explained before, and as shown in Figs. 21 and 22, the roller 14 rotates in a clockwise direction to wipe the plate as it moves from left to right. After the plate leaves the roller, its rotation continues a short distance to expose a clean portion of the material 15. At the beginning of the return movement of the plate, the roller rotates in a counterclockwise direction so that this clean portion of the material is used to polish the plate. Upon the next succeeding forward movement of the plate, the portion thus used for polishing is used for the wiping operation. As will be discussed hereinafter, the roller 14 is jogged or vibrated transversely of the machine (longitudinally of the axis of the roller) during the wiping and polishing operations.

Continuous tension is maintained in the strip of material 15 by the friction drive on the rewind roller 171. This drive is shown in Fig. 20. 180 indicates the axle carrying the roller 171. This 5 axle carries a pinion 181 engaged by the pinion 182. 183 indicates a driving pinion frictionally connected to the driven pinion 182 through the friction clutch mechanism indicated in general by 184, so that continuous rotation of the driving member 183 will maintain a continuous slipping drive against the member 182. The gear 183 is driven from the shaft 166 through the bevel gears 185 and 186.

187 indicates a friction brake on the shaft 15 158 carrying the feed roller 170 to prevent undesired over-running of the material 15.

Oscillations of the roller 14 are accomplished in the following manner. Drive is taken from the shaft 33 by means of the bevel gears 190 and 191 (see Fig. 12) to the vertical shaft 192 entering the gear box 193, shown in Figs. 12-19, inclusive. The mechanism in this gear box serves to oscillate and vibrate the roller 14 as originally described.

25 The oscillating of the roller is controlled by means of the cam roller 194 on the shaft 39, the surface of which is configured to operate the cam roller 195 on the rock shaft 196 pivoted at 197a. The rock shaft 196 controls the vertical rod 197 leading to the crank 198 connected to the shaft 199 entering the gear box 193. See Fig. 1. Oscillations of the shaft 199, caused by rocking of the arm 198, operate through the fingers 200 to move the shifting collar 201 and thus slide the pinion 30 202 splined to the shaft 203 to cause said pinion 202 to engage with either one or the other of the two reversely rotating loose driving pinions 204 and 205 on the shaft 203. These pinions 204 and 205 are continuously driven from the 35 driving shaft 206. The pinion 205 is driven from the pinion 207. The pinion 204 is driven in a reverse direction from the pinion 208 through the intermediate gear 209. The shaft 206 is driven by the bevel gear 210 which, in turn, 40 is driven from the bevel gear 211 on a shaft carrying the pinion 212 which, in turn, is driven by pinion 213 on the shaft 192.

The cam wheel 194 is so shaped that gear 202 will be shifted back and forth through the mechanism described to cause the roller 14 to oscillate as originally explained.

45 Drive from the shaft 203 is transmitted to the shaft 214 carrying the roller 14 through the gears 215, 216, 217 and 218. The gear 215 is on the shaft 203 and the gear 218 is on the shaft 214. Gears 216 and 217 are intermediate gears.

50 As explained before, the roll 14 is continuously vibrated or reciprocated transversely of the press, that is, longitudinally of the axis of the roll. This is accomplished in the following manner. The drive is effected from the pulley 219 on the shaft 220 driven by the belt 221 from the motor 222. The shaft 220 carries an eccentric 225 operating a fork 226 carrying the pin 227 to which is attached one end of the shaft 214 carrying the roller 14.

The arms 177 carrying the rollers 178 and 179 are mounted on the shaft 228 which is rockably supported in suitable bearings. By this arrangement suitable tension is maintained upon the runs of the material 15 leading to the roller 14 to permit oscillations of the latter. As shown in Fig. 21, the roller 14 is commencing to rotate clockwise. This will serve to raise the roller 178 55 and lower the roller 179 to the positions they

assume shown in Fig. 22, at which point the roller 14 is about ready to commence its rotation in the reverse direction. In other words, rollers 178 and 179 serve to apportion properly the slack in the material 15 between the roller 14 and the rollers 170 and 171.

Delivery conveyor

At the delivery end of the press is a delivery conveyor indicated in general by 17 in Fig. 22. This conveyor comprises continuously moving belts 129 and 231 carried on the rollers 232, 233 and 234. The rollers 232 and 234 are idler rollers, the belts being driven from 233 which, in turn, is driven through the gearing indicated in general by 235 and receiving the power from the motor 236 through the intermediate shaft 237 as shown in Fig. 4.

The bridging members 127 are rocked by means of rocking the shaft 128. This rocking is accomplished by a connection between the rod 250 and an arm on the shaft. The rod 250 carries a cam roller 251 engaging the cam 252 on a shaft 153. The roller 251 is held against the cam 252 by means of the spring 261 attached to the arm 260 carried by the shaft 128.

While there are shown and described certain embodiments of the invention, it is to be understood that it is capable of many modifications. Changes, therefore, in the construction and arrangement may be made without departing from the spirit and scope of the invention as disclosed in the appended claims, in which it is intended to claim all novelty inherent in the invention as broadly as permissible, in view of the prior art.

What I claim as new, and desire to secure by Letters Patent is:

1. In a printing press of the character described, means for wiping and polishing a plate, including: a strip of wiping material over a roller; means for reciprocating the plate; means for rotating the roller counter to the direction of movement of the plate during the wiping operation; means for continuing the rotation of the roller after completion of the wiping operation to expose a clean portion of the wiping material; and means for reversely rotating the roller during the reverse movement of the plate to cause such clean portion to polish the plate.

2. In a printing press of the character described, means for wiping and polishing a plate, including: a strip of wiping material over a roller; means for reciprocating the plate; means for rotating the roller counter to the direction of movement of the plate during the wiping operation; means for continuing the rotation of the roller after completion of the wiping operation to expose a clean portion of the wiping material; and means for reversely rotating the roller during the reverse movement of the plate to cause such clean portion to polish the plate, said portion being used for the next succeeding wiping operation.

3. In a printing press of the character described, means for wiping and polishing a plate, including: a strip of wiping material over a roller; means for exposing a portion of said strip for the wiping operation; means for wiping the plate with said portion; means for rotating the roller after completion of the wiping operation to expose a clean portion of the wiping material; and means for causing such clean portion to polish the plate, said portion then being used for the next succeeding wiping operation.

4. Apparatus as claimed in claim 3, with means

for causing relative bodily movement between the roller and plate and rotating the roller counter to the direction of such movement during the wiping operation.

5. Apparatus as claimed in claim 3, with means for causing relative bodily movement between the roller and plate and rotating the roller counter to the direction of such movement during the polishing operation.

6. Apparatus as claimed in claim 3, with means for causing relative bodily movement between the roller and plate and rotating the roller counter to the direction of such movement during the wiping and polishing operations.

10 7. Apparatus as claimed in claim 1, with means for transversely vibrating the roller during the wiping and polishing operations.

8. Apparatus as claimed in claim 2, with means for transversely vibrating the roller during the wiping and polishing operations.

15 20 9. Apparatus as claimed in claim 3, with means for transversely vibrating the roller during the wiping and polishing operations.

10. In a printing press of the character described, means for wiping and polishing the plate, including: a strip of material over a roller; and means for oscillating the roller.

25 30 11. In a printing press of the character described, means for wiping and polishing the plate, including: a strip of material over a roller; and means for oscillating the roller and vibrating it longitudinally of its axis.

12. In a printing press of the character described, means for wiping and polishing a plate, including: a strip of flexible, compressible, sheet material over a roller; means for oscillating said roller; a feed roller and rewind rollers for the ends of said strip of material; and means for taking up the slack in the strip of material between said first mentioned roller and said feed roller and said rewind rollers.

35 40 13. Apparatus as claimed in claim 12, in which the means for taking up the slack in the strip of material includes: a pair of rollers mounted on a rockable frame.

45 14. In a plate printing press, a wiping device for removing surplus ink from the surface of the printing plate, including: means for supporting a web of clean wiping material; a wiping roller; means for feeding said material over said roller; and means for imparting to said roller two distinct motions, one to pre-wipe said plate and another to effect final wiping thereof.

50 55 15. In a plate printing press, a wiping device for removing surplus ink from the surface of a moving printing plate, including: means for supporting a web of clean wiping material; a wiping roller; means for feeding said material over said roller in a direction counter to the movement of said plate; and means for imparting to said roller two distinct motions, one to pre-wipe said plate and another to effect final wiping thereof.

60 65 16. In a plate printing press, a wiping device for removing surplus ink from the surface of a reciprocating printing plate, including: means for supporting a web of clean wiping material; a wiping roller over which said web material is fed to thereby effect primary and final wiping; an onwinding roll arranged to receive web material traveling from said roller; and means for causing said material to advance at a constant speed during both the wiping operations and in a direction counter to the direction of movement of said plate in both cases.

70 75 17. In a printing press of the character de-

scribed, means for wiping and polishing a plate, including: means for reciprocating the plate; a strip of wiping material; means for effecting engagement between the strip and the plate during reciprocation thereof; means for moving the strip counter to the direction of movement of the plate during wiping thereof, and for continuing such movement after completion of the wiping operation to expose a clean portion of the material; and means for moving the strip in the

other direction during the reverse movement of the plate to cause such clean portion to polish the plate.

18. A printing press of the character claimed in claim 17, wherein such clean portion engages the plate, upon repetition of the first mentioned movement of the strip, to effect the next succeeding wiping operation.

10

JAMES EDWARD GILBERT.
